MANUFACTURE OF STOCKINGS
AND THE LIKE

Jean Garric, Troyes, France

Application September 11, 1947, Serial No. 773,473
In France May 14, 1947

2 Claims. (Cl. 66—82)

1

This invention relates to the manufacture of stockings, half-stockings and similar articles.

It is known that the shape of a woman's foot is such that the length of the stocking, when it is measured along the rearward middle line, that is to say along the seaming line for the stockings manufactured on flat knitting frames, must be in excess of about ten to twelve centimeters with respect to the length of the front middle line that follows the center line of the instep.

Besides, it is known that this result is readily achieved in the manufacture of the narrowed stockings having a "french" or "conventional" or "square" heel that are knitted on flat frames and the selvedges of which are thereafter assembled, forming thus the rearward middle line, this result being a consequence of the insertion, on each side of both selvedges, of a rectangle of about five by six centimeters, that is intended for fitting the wearer's heel, which in fact brings about an increase by ten to twelve centimeters of the length of the rearward middle line.

It is further known that in the simplified method of manufacture of the so-called "American heel" or "round heel" type that consists in effecting in succession widenings and narrowings in the width of the stocking blank, between the leg and the foot, there is actually obtained a certain knitted surface adapted to fit the wearer's heel, but nevertheless, no supplementary length is produced in the hind part. It is recognized that it results therefrom a very serious drawback, namely that in wear, the heel of the stocking has a propensity to slip under the wearer's foot, which is uncomfortable and brings about quick deformation and wear out of the stocking.

The invention has for its object to allow, in a relatively simple manner, the provision of the desired difference in length between the rear and the front middle lines of the stocking, without it being necessary to change the number of loops of certain rows as is done with the "conventional" or "square" heel.

To this end, the subject matter of the invention is an improvement in the manufacture of stockings and like articles, this improvement being characterised by the fact that, for obtaining a length of stocking greater in the hind part than in the front part, there is given to the loops of one and the same row, in the desired number of loop rows that are distributed over the whole length or a part of the length of the stocking, a greater length in the part intended to form the hind part of the stocking than in the part intended to form the front part, this being effected

without any interruption of any row in the median or central part of the stocking.

In the case of narrowed stockings that are knitted flat on straight bar knitting machines, the improvement will be brought about by varying the loop length, preferably in a progressive manner, in every one of the loop rows concerned, by knitting shorter loops in the center, and longer loops about the selvedge edges.

- 10 For putting into practice the improvement on a straight bar knitting machine of the cotton type, means, to which preference should presumably be given, consist essentially in transforming the loop control mechanism or device 15 through a modification of the profiles of the cam of the loop length regulating motion and of the splicing cam segments, so as to achieve, in the loop formation of each of the loop rows concerned, that the needle bar should be brought 20 progressively nearer the yarn sinking throats of the sinkers while couloring from one of the selvedge edges towards the center line of the stocking blank, which results in a progressive diminution of the length of the loops of the row 25 from the selvedge edge up to the center line, and then, that the said needle bar should be moved away with respect to the said throats from the center line towards the other selvedge edge, which results in a progressive lengthening of the loops.
- 30 For a better understanding of the invention and, at the same time, by way of example of embodiments, these various means are herein-after described, and diagrammatically illustrated in the accompanying drawings, wherein:
- 35 Fig. 1 shows the usual regulating motion controlling the loop length.

Fig. 2 shows, at an enlarged scale, the operating cam of the regulating motion with the modifications added thereto for obtaining a differential progressive loop length changing.

40 Fig. 3 shows the splicing cam segments that are also modified for the same purpose.

Referring to Fig. 1, illustrating the mechanism for regulating the loop length in a flat knitting frame of the Cotton type, 1 is the sinker head, provided at the bottom with the presser edge; in the grooves or slots of this head slide the sinkers 2 shut in by the top 3 of the same head; over this top lies the verge plate 4, against the edge of 50 which the backs 2^a of the sinkers 2 abut during the sinking of the loops.

5 is the needle bar, carrying the needles 6, and is swung through hinges 7 comprising fork-joints which are supported by the arms 22 keyed on the 55 needle bar shaft 23. To the needle bar 5 is im-

parted, for the presser action, an oscillation through a level 8, fixed by the middle of its length and keyed on an axle 9 connected to a rod 10 called "needle bar rocker arm," which is hitched to an axle 11 supported by the presser lever 12 attached to the presser lever shaft 13.

14 is the usual cam of the regulating motion that is keyed on the camshaft 15; a spring (not shown) keeps a roller 16, carried by the regulating lever 17, in contact with the cam 14, this cam 10 roller 16 acting upon the presser lever 12 through the intermediary of the regulating shaft 24 and of the adjustable contact device 18.

It is known that in the straight bar knitting machine of the Cotton type, the length of the loop is determined by the relative situation of the sinkers 2 and of the needles 6 in the course of the sinking of the loop. The situation of the sinkers 2 is governed by the verge plate 4, as the backs 2a of the sinkers abut against the edge of the verge plate. The situation of the needle bar is determined by the cam 14 of the regulating motion. With these machines, the line of the sinkers and that of the needles are straight and parallel to each other and their mutual situation remains unaltered during the whole sinking operation, owing to the fact that the cam 14 of the regulating motion has a concentric profile ABC during that time.

In order to obtain, in the practical embodiments of the improvements according to the invention, a progressive variation of the loop length, the profile or contour of the cam of the regulating motion is changed to A B¹ C (see Fig. 2) and thrown off center from O, which is the center of the camshaft 15, to O¹. Thus, the needle bar 5 will come progressively nearer, in the course of the sinking, when couloring from the selvedge edge towards the center, the camshaft rotating from A to B¹, which will cause a progressive shortening of the loop, a reverse result being obtained during the rotation from B¹ to C. The difference in the maximum length of the loop will be a function of the eccentricity BB¹ or OO¹.

The normal loop length regulation being thus modified, it should be also necessary to modify the loop length regulation for the spliced sections. It is known that for the splicing, the camshaft 15 bears segments 19 and 20 having concentric outer edges AD and CE (Fig. 3), that are displaced in their plane for following the changes in the profile of the splicing by means of directing grooves or slots 21. The outer profiles A'D' and C'E' of the

cam segments 19 and 20 are offset with respect to the axis of the shaft 15 by the same amount OO¹ as for the normal loop length regulation and the groove 21 directing them through their displacement is similarly concentric with O¹ instead of O. Thus the mutual situation of the splicing cam segments 19 and 20 and the regulating cam 14 remains the same, whatever be the profile of the spliced portion. Consequently, during knitting of spliced or of ordinary portions alike, the loops will be progressively longer about the selvedge edges than in the center of the stocking.

I claim:

1. In a knitting machine of the Cotton type, the combination with a needle bar of regulating motion mechanism for actuating the needle bar and comprising a cam shaft, a regulating motion cam mounted on the shaft, a cam follower and operative connections between the cam follower and the needle bar whereby the needle bar is moved in accordance with the profile of the cam, that portion of the cam profile which controls the position of the needle bar during sinking being eccentric of said shaft so as to produce, in the formation of each row of loops on the needle bar, a progressive approach of the needle bar nearer to the yarn sinking throats of the sinkers when couloring from one of the selvedge edges towards the center line which results in a progressive shortening of successive loops, and thereafter produce a progressive movement of the needle bar farther away from the yarn sinking throats of the sinkers when couloring from the center line to the other selvedge edge which results in a progressive lengthening of successive loops.

2. Mechanism according to claim 1, whereby the profiles of the splicing cam segments are similarly eccentric of the cam shaft.
